ELECTRIC TIMER FOR TOASTERS

James Geier, Troy, N. Y., assignor, by mesne assignments, to McGraw Electric Company, Chicago, Ill., a corporation of Delaware

Application March 23, 1935, Serial No. 12,587
Renewed October 16, 1939

19 Claims. (Cl. 219—19)

This invention relates to electrical toasters and the like and refers more particularly to time retarded cut-off switches or automatic circuit breakers for governing the supply of heat to 5 electrical heating resistances.

An object of the present invention is the provision of an electric timing unit for electrical toasters which would eliminate commonly used 10 clock works, and which is inexpensive, reliable 10 and quick in operation.

Another object is the provision of an automatic circuit breaker by means of which the period of time during which an electrical toaster or any other suitable electrical device is operated, 15 can be easily and conveniently adjusted.

A further object is the provision of an electrical heating device comprising an indicating device in the form of a bell and the like, for the purpose of indicating the interruption of the flow 20 of electrical current through the heating resistances.

The above and other objects of the present invention may be realized through the provision of an automatic circuit breaker comprising an 25 expansible and contractible heat-responsive member, such as a bi-metallic strip, adapted to maintain a switch in its closed position for a predetermined period of time, which corresponds to the time during which the heating resistances of a 30 toaster are supplied with an electrical current and which may be varied by varying the period of contact between the bimetallic strip and the switch.

The invention will appear more clearly from 35 the following detailed description when taken in connection with the accompanying drawings showing preferred embodiments of the inventive idea.

In the drawings:

40 Figure 1 shows a toaster in side elevation.

Figure 2 shows in vertical section the automatic cut-off switch of the toaster, the section being taken along the line 2—2 of Figure 3.

45 Figures 3, 4 and 5 illustrate diagrammatically the automatic cut-off switch of the toaster in three different positions in a bottom plan view.

Figure 6 shows in side elevation a toaster provided with a separate cut-off switch.

50 Figures 7, 8 and 9 are top views of the switch shown in Figure 6, with the cover removed, illustrating the switch in three different positions.

The toaster illustrated in Figures 1 to 5 of the drawings, comprises a casing 10 containing the usual heating elements or resistances 11 (Figs. 3, 55 4 and 5) and provided with a cover 12. The toaster is supported by a casing 13 which contains the automatic cut-off switch and which is provided with a suitable opening for the cable 14 containing a pair of conducting wires 15 and 16, 60 illustrated diagrammatically in Figures 3 to 5.

The wire 15 is connected with a switch or a contact 16¹. The switch 16¹ comprises a conducting piece 17 connected with the wire 15 and a conducting piece 18 connected with a wire 19. The conducting pieces 17 and 18 are separated from each other by insulation and may be operatively connected with each other by a conducting abutment 20, for the purpose of transmitting an electrical current from the wire 15 to the wire 19, as will be described hereinafter. 10

The abutment 20 forms a portion of a lever 21 which is rotatably mounted upon a pivot 22 situated intermediate the two ends of the lever 21. One end of the lever 21 is connected with a spring 23 attached at 24 to the casing 13. The opposite 15 end of the lever 21 carries a pin 25 which is adapted to come in contact with an abutment 45 of a bi-metallic strip 42.

A stop 26 is fixed to the casing 13 and is used for preventing the rotation of the lever 21 beyond the position shown in Figure 3. 20

The pivot 22 also passes through one end of an adjusting lever 27 which is rotatably mounted upon a pivot 28 and which may be set by the operator in any one of the different positions indicated by the openings 29. 25

The opposite end of the wire 19 is connected to the main heating resistances 11.

A wire 30 connected to the opposite end of the heating resistances 11 is attached to a conducting 30 piece 31 of a contact or switch 32.

The switch 32 which is similar to the switches 16¹ and 33 is shown in end elevation in Figure 2 of the drawings and comprises a conducting piece 31 which is separated from the conducting piece 34 by a piece of insulation 35. The conducting piece 34 is attached to one end of the wire 16. 35

A lever 36 may be used for the purpose of establishing an electrical connection between the wires 30 and 16. This is accomplished when a portion of the lever 36 is situated between the conducting pieces 31 and 34. 40

The lever 36 comprises an insulated end 37 projecting out of the casing 13 and used for the purpose of switching on the electrical toaster. 45

The lever 36 is rotatably mounted upon a pivot 38 situated intermediate the two ends 37 and 39 of the lever 36.

The end 39 of the lever 36 is curved and adapted to come in contact with the lever 21, so that the lever 21 is actuated when the lever 36 is moved. 50

The lever 36 also carries a projection 40 made of an insulating material and adapted to project into an opening 41 formed in the bi-metallic strip 42, as will be described hereinafter. 55

The bi-metallic strip 42 is attached by bolts or rivets 43 to a bracket 44 connected to the walls of the casing 13, and is heated by a wire 46 surrounding a portion of the strip 42 and 60

having one end which is connected to the wire 16 at 59. The opposite end of wire 46 is connected to a conducting piece 47 of the contact or switch 33. Another conducting piece 48, separated by insulation from the conducting piece 47, is attached to one end of a wire 49 which is connected at 50 to the wire 30 leading from the resistances 11 to the contact 32.

The lever 36 is usually maintained in the position shown in Figure 3 by the spring 51, one end of which is attached to the lever 36, while its opposite end is connected to the casing 13.

In the position shown in Figure 3, the lever 36 is situated between the conducting pieces 31 and 34, so that an operative electrical connection is established between the wires 30 and 16. However, in this position, no electrical current will flow through the circuit as there is no electrical connection between the wires 15 and 19, since there are no conductors operatively interconnecting the conducting pieces 17 and 18. Furthermore, there is no electrical connection between the wires 46 and 49, since no conductors interconnect the conducting pieces 47 and 48 of the switch 33.

In order to switch the toaster on, the end 37 of the lever 36 is moved by hand from the position shown in Figure 3 to the position shown in Figure 4. In the course of this movement, the lever 36 rotates clockwise and its end 39 pushes the lever 21, which also swings in a clockwise direction, until the projection 20 of the lever 21 is inserted between the two conducting pieces 17 and 18 of the switch 16.

The lever 36 is moved in this direction until its projection 40 snaps into the opening 41 provided in the bi-metallic strip 42. Then the lever 36 is held in the position shown in Figure 4 by the projection 40. In this position, the lever is situated between the conducting pieces 47 and 48 of the contact 33, so that an operative electrical connection is established between the wires 46 and 49.

The electrical energy supplied by any suitable source of electrical energy will cause the flow of an electrical current through the wire 15, the contact piece 17, the projection 20, the contact piece 18, the wire 19, and the electrical heating resistances 11.

In the position shown in Figure 4, there is no operative electrical connection between the conducting pieces 31 and 34 of the switch 32, so that the electrical current leaving the resistances 11 flows through the wire 30 as far as the connecting point 50, and then flows through the wire 49, the conducting piece 48 of the switch 33, the adjacent portion of the lever 36, the conducting piece 47 and the wire 46 connected at 59 with the wire 16.

Therefore, in the position shown in Figure 4, both the resistances 11 and the bi-metallic strip 42 are heated by the current flowing through the electrical circuit.

The wire 46 will gradually heat the bi-metallic strip 42 until this strip begins to expand and moves from the position shown in Figure 4 to the position shown in Figure 5. When the bi-metallic strip 42 is moved to this extent, it moves out of reach of the projection 40 carried by the lever 36, so that the projection 40 is freed from the opening 41 provided in the bi-metallic strip 42.

As soon as the projection 40 loses its contact with the edges of the opening 41, the spring 51 pulls the lever back from the position shown in

Figure 4 to the position shown in Figure 5, which is substantially the same position as that illustrated in Figure 3. In these positions a portion of the lever is inserted between the conducting pieces 31 and 34 of the contact 32, so that a positive electrical connection is established between the wires 30 and 16.

Although the lever 36, by swinging counter-clockwise, moves out of contact with the lever 21, the lever 21 will not be moved to any considerable extent by its spring 23, since, due to the expansion of the bi-metallic strip 42, its abutment 45 is brought in contact with the pin 25 carried by the lever 21; consequently, in the position shown in Figure 5, the lever 21 is maintained by the abutment 45 in substantially the same position as that shown in Figure 4, so that the projection 20 of the lever 21 continues to maintain an operative connection between the conducting pieces 17 and 18 of the switch 16.

In the position shown in Figure 5, an electrical current flows through the wire 15, the conducting piece 17, the projection 20 of the lever 21, the conducting piece 18, the wire 19 and the electrical heating resistances 11. Since the connection between 49 and 46 is interrupted, the current leaving the resistances 11 will flow through the entire wire 30, the conducting piece 31, the adjacent portion of the lever 36 the conducting piece 34 and the wire 16.

Therefore, in the position shown in Figure 5, the electrical heating resistances 11 continue to be supplied by the electrical current while the bi-metallic strip 42 is not heated any more by the coil 46. Consequently, the bi-metallic strip 42 will gradually cool off and will slowly move from the position shown in Figure 5 back into the position shown in Figure 3. In the course of this movement, the bi-metallic strip 42 will assume a certain intermediate position in which the contact between the pin 25 carried by the lever 21, and the abutment 45 forming a part of the bi-metallic strip 42 will be interrupted, so that the spring 23 will be able to pull the lever 21 from the position shown in Figure 5 to the position shown in Figure 3, thereby interrupting the electrical connection between the wires 19 and 15.

The object of the lever 21 is to vary the time of this interruption of contact between the pin 25 and the abutment 45. The various positions of the lever 21 correspond to the different positions of the pin 25 in relation to the abutment 45 at the time when the strip 42 moves out of contact with the lever 21, while the various positions of the pin 25 correspond to different periods of time during which the pin 25 is maintained in contact with the abutment 45 and the electrical heating resistances 11 are supplied with the electrical current.

The modification shown in Figs. 6 to 9 comprise a separate automatic circuit breaker situated in a casing 60 and connected by a cable 61 with the heating resistances situated within the toaster 62 (Fig. 6).

As shown in Figures 7 to 9, the circuit breaker situated within the casing 60 comprises a socket 63 adapted to carry a plug 64 attached to one end of the cable 61. The socket 63 carries two ends of conducting wires 65 and 66.

The opposite end of the wire 65 is attached to a bolt 67 operatively connected to and supporting a resilient strip 68 made of a conducting material.

A lever 69 is rotatably mounted upon a pivot 70.

One end of the lever 69 is attached at 71 to an end of a coil spring 72, which tends to maintain the lever 69 in the position shown in Figure 7. The middle portion of the lever 69 is provided with curved edges 73 which may come in contact with the edges 74 of a lever 75. The opposite end 76 of the lever 69 carries a rod 77 provided with a hammer 78 which is adapted to strike a bell 79 attached to the casing 60. The lever 69, the rod 77 and the hammer 78 are usually stamped of one piece.

The lever 69 also carries a pivot 80; both the pivot 80 and the lever 69 are made of a conducting material.

The lever 75 is rotatably mounted intermediate its ends upon a pivot 81 and is provided with a curved end portion 82 having the edges 74. The opposite end 83 of the lever 75 projects outside of the casing 60 and is made of an insulating material. The end portion 83 of the lever 75 is used as a handle in a manner which will be described hereinafter.

A lever 84 is mounted upon a pivot 85 and carries the pivot 81 around which the lever 75 may be rotated. The opposite end portion 86 of the lever 84 is bent and is provided with an insulated handle 87 which projects out of the casing 60. The position of the lever 84 may be adjusted by moving the handle 87, thereby adjusting the position of the pivot 81 and of the lever 75.

The casing 60 carries a stop 88 which limits the movement of the lever 75.

The lever 75 also carries a pin 89 which is made of insulated material and which is adapted to come in contact with the edges 90 of the bi-metallic strip 91.

In the position shown in Figure 8, the pin 89 is in contact with the shoulder 92 of the strip 91.

The strip 91 is connected by bolts 93 with a bracket 94 which is attached to the casing 60.

The lever 75 is maintained in the position shown in Figure 7 by means of a spring 95 one end of which is attached to the lever 75, while its opposite end is connected to a pin carried by the casing 60.

The bi-metallic strip 91 is heated by a coil 96 surrounding a portion of the strip 91. One end of the coil 96 is connected to one of the bolts 93, while the opposite end of the coil 96 is attached to the pivot 85.

One end of the wire 97 is connected to one of the bolts 93 made of a conducting material. The two wires 66 and 97 are insulated from each other and are surrounded by insulation forming a cable 98. As shown in Figure 6, the cable 98 is provided with a plug 99 which may be connected to any suitable source of electrical energy.

In the position shown in Figure 7, no current will flow through the device, since there is no connection between the strip 68 and the lever 69. Furthermore, there is no electrical connection between the bi-metallic strip 91 and the lever 69.

In order to switch on the device, the handle 83 is moved by hand from the position shown in Figure 7 to the position shown in Figure 8. In the course of this movement, the lever 75 rotates clockwise and the edges 74 of its end portion 82 come in contact with the edges 73 of the lever 69. The lever 69 is caused to swing counter-clockwise by the lever 75 until it assumes the position shown in Figure 8 of the drawings.

In this position, the lever 69 is in contact with the strip 68 so that a positive electrical connection is established between these two members.

While the lever 75 is moved clockwise, its insulated pin 89 slides along the edges 90 of the bi-metallic strip 91 until the pin 89 passes beyond the shoulder 92 of the strip 91.

As shown in Figure 8, the pin 89 is then held by the shoulder 92 so that the lever 75 is prevented from returning to its original position shown in Figure 7. In the position shown in Figure 8, the edges 74 of the lever 75 are in contact with the edges 73 of the lever 69. An operative electrical connection is thereby established between the lever 69 and the lever 75.

The electrical energy supplied by any suitable source not shown in the drawings, will cause a flow of electrical current through the plug 99 15 and the cable 98. This electrical current will flow through the socket 63, the plug 64 and the cable 61, passing through the electrical heating resistances situated in the toaster 62 and heating these resistances. An electrical current will flow through the wire 65, the strip 68, the lever 69, the lever 75, and the lever 84. The current passing through the lever 84, will flow through the coil 96, and the wire 97, returning to the source of electrical energy through the cable 98. 25

Therefore, in the position shown in Figure 8, the resistances situated in the toaster 62 and the bi-metallic strip 91, are both heated by the current flowing through the electrical circuit.

The coil 96 will gradually heat the bi-metallic strip 91 until the strip begins to expand and moves from the position shown in Figure 8 to the position shown in Figure 9. While the bi-metallic strip 91 is moved to this extent, the shoulder 92 is moved out of reach of the pin 89 35 carried by the lever 75, with the result that the lever 75 is freed and is pulled back by its spring 95, moving from the position shown in Figure 8 to the position shown in Figure 9, which is similar to that shown in Figure 7. 40

In this position, there is no electrical contact any more between the lever 69 and the lever 75, so that there is no electrical current flowing through the coil 96.

Although the lever 75, by swinging counter-clockwise, moves out of contact with the lever 69, the lever 69 will not be moved to any considerable extent by its spring 72, since the pin 80 of the lever 69 will drop upon the surface 100 of the bi-metallic strip 91 and will be supported by this surface as soon as the lever 75 is moved out of reach of the lever 69. This position is shown in Figure 9 of the drawings. In this position, the lever 69 is maintained in contact with the strip 68 by the surface 100 of the 55 bi-metallic strip 91. The electrical current will, therefore, continue to flow through the heating resistances situated within the toaster 62 and will also flow through the wire 65, the strip 68, the lever 69, the pin 80, the bi-metallic strip 91, 60 and the wire 97.

While an electrical current is thus caused to flow through the heating resistances situated within the toaster 62, the coil 96 will not be heated any more, so that the bi-metallic strip 91 will 65 gradually begin to cool off and will slowly move from the position shown in Figure 9 back to the position shown in Figure 7. While the bi-metallic strip 91 is carrying out this movement, the pin 80 of the lever 69 slides along the surface 100 70 of the strip 91 until it reaches the edge 101 of this strip. As soon as the pin 80 passes beyond this edge, the lever 69 is freed from contact with the strip 91, with the result that the spring 72 is able to pull the lever 69 from the position 75

shown in Figure 9 to the position shown in Figure 7, thereby interrupting the operative electrical connection between the strip 68 and the lever 69; the hammer 78 strikes against the bell 79, thus indicating that the heating operation has been completed.

The object of the lever 84 is to vary the time of this interruption of contact between the pin 80 and the surface 100 of the bi-metallic strip 91. The position of the lever 84 may be adjusted by the insulated handle 87 projecting out of the casing 60. The various positions of the lever 84 correspond to different positions of the pin or pivot 81 around which the lever 75 is oscillated. The different positions of the pin 81 correspond to different positions of the lever 75 at the time when the insulated pin 89 is engaged by the shoulder 92 of the bi-metallic strip 91. On the other hand, these various positions of the lever 75 correspond to different positions of the pin 80 at the time when the pin 80 is brought in contact with the surface 100 of the bi-metallic strip 91. Finally the different positions of the pin 80 at the time of its contact with the surface 100 correspond to different periods of time during which an electrical circuit is maintained which supplies an electrical current to the heating resistances within the toaster 62.

What is claimed is:

- 30 1. Means for automatically interrupting the flow of electrical current to a main heating resistance, said means comprising a switch, means connecting said switch to the main heating resistance and to a source of electrical energy, a heat-responsive expansible and contractible member, means connected with said heat-responsive member to maintain said switch in its closed position while said heat-responsive member is expanded, electrical heating means for heating said heat-responsive member to expand the same, means connecting said electrical heating means to said source of electrical energy, a lever which is movable from an inoperative position to an operative position, said lever while so moved moving said switch and closing the same and thereby establishing an electrical circuit causing a flow of electrical current from said source and through said main heating resistance, a member which is carried by said lever, means constituting a part of said heat-responsive member for locking the last-mentioned member, said lever being maintained in its operative position while said heat-responsive member is not expanded when the last-mentioned member is locked by the last-mentioned means, means connected with said electrical heating means for causing a flow of said electrical current through said electrical heating means while said lever is in its operative position, and means connected with said lever for returning the same to its inoperative position after the expansion of said heat-responsive member, whereby the flow of electrical current through said electrical heating means is interrupted while said heat-responsive member, while expanded, maintains said switch in its closed position.
2. Means for automatically interrupting the flow of electrical current to a main heating resistance, said means comprising a switch, means connecting said switch to the main heating resistance and to a source of electrical energy, said switch comprising a rotatable member movable to an operative position wherein said switch is closed; a heat-responsive expansible and contractible member, means connected with said heat-responsive member to maintain said ro-

tatable member in its operative position while said heat-responsive member is expanded, a coil connected to said source of electrical energy for heating said heat-responsive member, a pair of conducting pieces, one of which is connected with 5 said coil, the other being connected to the main heating resistance, another pair of conducting pieces, one of which is connected to said source of electrical energy, the other one being connected to the main heating resistance, a rotatable lever which is movable from an inoperative to an operative position, said lever in its inoperative position interconnecting electrically the last-mentioned pair of conducting pieces, said lever in its operative position interconnecting electrically 10 the first-mentioned pair of conducting pieces, and means for moving said lever into its inoperative position after the expansion of said heat-responsive member.

3. Means for automatically interrupting the flow of electrical current to a main heating resistance, said means comprising a pair of conducting pieces, means connecting one of said connecting pieces with said main heating resistance, means connecting the other one of said 25 conducting pieces to a source of electrical energy, a rotatable lever movable from an open position to a closed position, said lever interconnecting electrically said pair of conducting pieces in the closed position of said lever, a pin carried by said 30 lever, a heat-responsive expansible and contractible member, a member carried by said heat-responsive member and establishing a contact with said pin after the expansion of said heat-responsive member, whereby said lever is maintained in its closed position while said heat-responsive member is expanded, a coil surrounding a part of said heat-responsive member and connected to said source of electrical energy, another pair of conducting pieces, one of which is 35 connected with said coil, the other being connected to the main heating resistance, a third pair of conducting pieces, one of which is connected to said source of electrical energy, the other one being connected to the main heating 40 resistance, a rotatable lever movable from an operative to an inoperative position, the last-mentioned lever interconnecting electrically the last-mentioned pair of conducting pieces in its inoperative position, the last-mentioned lever in its 45 operative position interconnecting electrically the second-mentioned pair of conducting pieces and maintaining the first-mentioned lever in its closed position, a projection carried by the last-mentioned lever and projecting through an opening 50 formed in said heat-responsive member in the operative position of the last-mentioned lever and while the heat-responsive member is not expanded, and a spring connected with the last-mentioned lever and moving it into its inoperative position after the expansion of said heat-responsive member.

4. Means for automatically interrupting the flow of electrical current to a main heating resistance, said means comprising a pair of conducting pieces, means connecting one of said connecting pieces with said main heating resistance, means connecting the other one of said 65 conducting pieces to a source of electrical energy, a rotatable lever movable from an open position to a closed position, said lever interconnecting electrically said pair of conducting pieces in the closed position of said lever, a pin carried by said lever, a heat-responsive expansible and contractible member, a member carried by said heat- 70 responsive member to maintain said ro-

- responsive member and establishing a contact with said pin after the expansion of said heat-responsive member, whereby said lever is maintained in its closed position while said heat-responsive member is expanded, a coil surrounding a part of said heat-responsive member and connected to said source of electrical energy, another pair of conducting pieces, one of which is connected with said coil, the other being connected to the main heating resistance, a third pair of conducting pieces, one of which is connected to said source of electrical energy, the other one being connected to the main heating resistance, a rotatable lever movable from an operative to an inoperative position, the last-mentioned lever interconnecting electrically the last-mentioned pair of conducting pieces in its inoperative position, the last-mentioned lever in its operative position interconnecting electrically the second-mentioned pair of conducting pieces and maintaining the first-mentioned lever in its closed position, a projection carried by the last-mentioned lever and projecting through an opening formed in said heat-responsive member in the operative position of the last-mentioned lever and while the heat-responsive member is not expanded, and a spring connected with the last-mentioned lever and moving it into its inoperative position after the expansion of said heat-responsive member, a spring connected with the first-mentioned lever to return the same to its open position, and means connected with the first-mentioned lever for adjusting the position thereof relatively to said heat-responsive member, thereby varying the time during which the first-mentioned lever is maintained in its closed position by the heat-responsive member.
5. Means for automatically interrupting the flow of electrical current to a main heating resistance, said means comprising a strip connected with said main heating resistance and with a source of electrical energy, a lever movable from an inoperative position to an operative position, a pin carried by said lever, a spring connected with one end of said lever to maintain the same in its inoperative position, a heat-responsive expansible and contractible member having a shoulder and a surface which, while said heat-responsive member is expanded, contacts said pin, thereby maintaining said lever in its operative position, in which said lever is in electrical contact with said strip, a coil surrounding a part of said heat-responsive member for heating the same and connected with said source of electrical energy, a lever movable from an operative position to an inoperative position, the second-mentioned lever contacting the first-mentioned lever to maintain the same in contact with said strip while the second-mentioned lever is in its operative position, a pin carried by the second-mentioned lever and engaging said shoulder in the operative position of the second-mentioned lever and while said heat-responsive member is not expanded, a spring connected with the second-mentioned lever for moving the same into its inoperative position after the last-mentioned pin has been released by the expansion of the heat-responsive member, and means electrically connecting said coil with the last-mentioned lever.
6. Means for automatically interrupting the flow of electrical current to a main heating resistance, said means comprising a strip connected with said main heating resistance and with a source of electrical energy, a lever movable from an inoperative position to an operative position, a pin carried by said lever, a spring connected with one end of said lever to maintain the same in its inoperative position, a heat-responsive expansible and contractible member having a shoulder and a surface which, while said heat-responsive member is expanded, contacts said pin, thereby maintaining said lever in its operative position, in which said lever is in electrical contact with said strip, a coil surrounding a part of said heat-responsive member for heating the same and connected with said source of electrical energy, a lever movable from an operative position to an inoperative position, the second-mentioned lever contacting the first-mentioned lever to maintain the same in contact with said strip while the second-mentioned lever is in its operative position, a pin carried by the second-mentioned lever and engaging said shoulder in the operative position of the second-mentioned lever and while said heat-responsive member is not expanded, a spring connected with the second-mentioned lever for moving the same into its inoperative position after the last-mentioned pin has been released by the expansion of the heat-responsive member, and means electrically connecting said coil with the last-mentioned lever.
7. In a bread toaster, a toasting compartment, a thermally responsive device, means mechanically connected to said thermally responsive device during cooling thereof for directly terminating the toasting of a bread slice in said toaster responsive to movement and return of said thermally responsive device by heating and cooling the same.
8. In a heat treating apparatus, means for establishing intervals of the heat treating action including, a thermally responsive member, and means mechanically connected to said thermally responsive member for directly terminating a heat treating action in response to cooling of said thermally responsive member.
9. In a cooking device having food heating means, timing means for establishing intervals of the cooking action including a thermally responsive member having a portion movable in response to temperature changes, and a heater operative on said member only until the latter has reached a predetermined high temperature; and means mechanically connected to said thermally responsive member for directly terminating the cooking action by said food heating means in response to cooling movement of said thermally responsive member, said thermally responsive member being permitted to cool after said predetermined high temperature is reached and said food heating means being operative during the cooling of said member.
10. In a toaster adapted to be used in carrying out a plurality of successive toasting operations and having an electrical toast heating element energized only during toasting operations, a main electric switch for said main toast heating element, a timer for establishing intervals of the toasting action including a thermally responsive member, an electric heater for heating said member thereby to cause movement thereof, means for energizing said heater, and means responsive to heating movement of said thermally responsive member for rendering said heater inoperative thereby to permit said member to cool; means for energizing said toast heating element, and means mechanically connecting said main switch and said thermally responsive member during

- cooling thereof for opening said main switch responsive to cooling movement of the thermally responsive member after the heater is rendered inoperative.
5. 11. In a cooking device of the type adapted to be used in carrying out a plurality of successive actions, a timer for establishing intervals of the cooking action including a thermally responsive member, a heater for heating said member there-
10 by to cause movement thereof, means for instituting operation of said heater upon the institution of a cooking interval, and means responsive to heating movement of said thermally responsive device for rendering said heater inoperative
15 thereby to permit the thermally responsive member to cool; and means mechanically connected to said thermally responsive member during cooling thereof for directly terminating a cooking action responsive to cooling movement of said thermally responsive member after said heater is rendered inoperative, for interrupting the cooking action of said device.
12. In a heat treating apparatus, means for establishing intervals of the heat treating action including, a thermally responsive member having a portion movable in response to temperature changes, and means mechanically connected to said thermally responsive member and biasing the same in cooling direction during cooling thereof for directly terminating a cooking action in response to cooling of said thermally responsive member.
13. In a cooking device of the type adapted to be used in carrying out a plurality of successive cooking actions, having an electrical cooking element and a main switch therefor, a timer for establishing intervals of the cooking action including a bimetallic warp acting member, a heater for heating said member to cause movement thereof, means for instituting operation of said heater upon institution of a cooking interval, and means responsive to heating movement of said bimetallic member for rendering said heater inoperative thereby to permit the thermally responsive member to cool; means normally biasing said switch to open position, and mechanical means connecting said bimetallic member and said switch during cooling thereof, said thermally responsive member being biased in cooling direction during cooling thereof by said switch biasing means and being operative to prevent opening of said switch by said biasing means until said member has cooled to a predetermined temperature.
14. The combination with an electric heating means, of means for timing the operation thereof, said means comprising a thermally-responsive element, a support therefor, means for moving a part of said thermally responsive element while setting up an increasing force therein and for returning it by heating and cooling the thermally responsive element, and means for utilizing a decrease of force of said thermally responsive element when cooling to time the duration of operation of said heating means.
15. Means for controlling the energization of an electric heating means comprising a switch normally biased to open position, means for closing said switch and holding it closed, a bimetal bar constructed and arranged to mechanically hold said switch closing means in switch-holding position, an auxiliary electric heater energized by said switch closing means to heat said bimetal bar and cause it to release said switch closing and holding means to deenergize the auxiliary heater, and to hold said switch in closed position when the temperature of the bar has been raised to a given value, the bimetal bar then cooling and holding said switch closed with decreasing force until the temperature of the bar has been reduced to a given value.
16. In a heat treatment apparatus, an electric heating means, a control switch therefor movable into closed and open positions, means for causing opening of said switch set by closing movement of the switch, a bimetal bar, means including said bimetal bar for locking said switch in closed position, means for heating and cooling said bimetal bar, means controlled by said bimetal bar when it has been heated to a given temperature for causing release movement of the switch locking means, and for holding said switch in closed position until a predetermined degree of cooling of the bimetal bar has taken place.
17. Means for controlling the energization of an electric heating means comprising a control switch therefor, means normally yieldingly biasing said switch into open position, a bimetal bar, means movable into locking engagement with said bimetal bar to cause closing of said switch and holding it in closed position, means for moving the free end of said bar and returning it by heating and cooling the bar, the bar releasing said switch closing means when heated to a given temperature and then causing holding of the switch in closed position against the transmitted stress of the switch biasing means until its movement incident to its cooling causes opening movement of the switch.
18. Means for automatically interrupting current flow through an electric heating means comprising a thermal element, an auxiliary electric heater therefor, a lever arm, means actuatable by said lever arm to cause energization of said electric heating means and said electric heater, means on said lever arm engageable with said thermal element when the latter is below a predetermined temperature for holding said lever arm in said energizing position, means for returning said lever arm to heater deenergizing position when said thermal element has reached a predetermined high temperature, the thermal element then acting to cause continuance of the energization of the electric heating means until the temperature of the thermal element has reached a predetermined low value.
19. In an automatic toaster, a toasting heater, a control switch therefor, a bimetal bar, an electric heater for the bar, a lever arm movable to cause closing of the switch and also cause energization of the heater for the bar, means on the bar engageable with said lever arm to hold the latter in switch-closing position when the bar is below a predetermined temperature but operative to release said arm when said temperature is exceeded, means connected with the lever arm to move the same when disengaged from the bar when the latter has been heated to thereby de-energize the bar heater, and means on the bar effective when the bar is heated to hold the switch closed and to retain it closed until the temperature of the bar has decreased to a given value.

JAMES GEIER.
